UNITED STATES PATENT OFFICE.

SAMUEL L. SAUNDERS, OF LYNN, MASSACHUSETTS.

RACK FOR HOLDING BOOTS AND SHOES.

SPECIFICATION forming part of Letters Patent No. 380,938, dated April 10, 1888.

Application filed December 3, 1887. Serial No. 256,850. (No model.)

To all whom it may concern:

Be it known that I, SAMUEL L. SAUNDERS, of Lynn, in the county of Essex and Commonwealth of Massachusetts, have invented certain Improvements in Boot and Shoe Racks, of which the following, taken in connection with the accompanying drawings, is a specification.

This invention relates to devices for holding boots and shoes while in the factory undergoing the process of being manufactured; and it is the object of the invention to provide means for supporting boots and shoes in such manner as to prevent their being jammed and crushed or broken by coming in contact with or being piled upon each other; also, to permit the shoes to be moved about from one point or room in the factory to some remote point or room in the factory; and other less important purposes, as well as the nature and operation of the invention, will be fully described, and specifically pointed out in the claims hereinafter written.

Referring to the drawings, Figure 1 is a plan view of a shoe-rack embodying my invention. Fig. 2 is an end elevation thereof. Fig. 3 is a sectional detail; and Fig. 4 is a perspective view of a detail, to be referred to hereinafter.

The rack is provided with a skeleton framework composed of the base A, vertical bars or standards B, cross bars D, and suitable stay-rods, d, all combined and firmly bound together, as represented in the drawings. The bars H, respectively, have their ends journaled in the cross bars D, so as to permit rocking movement, and the pins e, upon which the shoes are placed for support, are fixed firmly in the bars H and project horizontally outward from the bars, as shown.

On the rear end of the pins e are other bars or rods, N, which are secured firmly on the ends of the pins, and are further provided with upwardly-extended back-boards h. The ends of the bars N are also connected by the vertical rods or bars S. The connection is made by suitable pin-joints to prevent cramping when the pins e are tilted, as referred to hereinafter.

In using the rack it is oftentimes most convenient to have the pins e project outward in a straight or horizontal position. The shoes may be most conveniently placed in position

or removed from the rack, and especially from the top shelves thereof, when the pins are in the horizontal position; but while moving the rack from place to place about the factory it is quite desirable to have the pins e elevated, their outer ends being above the horizontal plane, and to this end the supporting-bars H have their ends journaled in the cross-bars D, so as to permit the rocking movement required in changing the pins from the elevated to the horizontal position. The bars S are respectively connected with each of the bars N that come in the same vertical plane with the bars S, and by this means all pins having support in the bars connected by any particular bar S will be given a regular and uniform movement or elevation, and the whole system may be elevated or depressed by simply lifting and depressing the bar S which controls the system.

On top of the rack are boards f f, which serve, respectively, as back-boards to the top-most rows of pins, as represented. The boards f have their ends journaled in the frame of the rack, and have in their bottom edge faces the respective notches n, and between the boards f is a spring, P, (see Fig. 3,) that operates to open apart the bottom edges of the boards. When the bars S are either of them depressed and the system of pins therewith connected are elevated to the inclined position, then it is that the notch n of the corresponding board f will receive the edge or corner of the topmost bar, N, and the pins will be thereby prevented from returning to the horizontal position until the board f is first pressed inward against the action of spring P, and the said bar N is thus released and allowed to again move upward. The pins are further prevented from going below the horizontal position, and are maintained in the horizontal position by reason of the bar N coming to and bearing upward against the shoulder t. (See Fig. 3.)

The shoe is placed for support upon the pins, as represented, the leg being suspended downward between the supporting-pins, the vamp portion bearing upon the cross-bar H. This arrangement prevents the upper of the shoe from getting crushed or marred by coming into engagement with each other or with external hard substances. To further insure the absolute separation of the shoes, the pins e are ar-

ranged in pairs, so that no two shoes bear upon the same pin. When about to be moved, the pins are tilted to the inclined position, and all jarring of the rack while being moved will 5 cause the shoes to press and move forward over the bar H, and in this way the shoes are retained upon the rack without being bound there.

I claim—

1. A rack for holding boots and shoes, consisting of a frame-work made up of a suitable base and end standards, supporting-bars arranged between the sections of the frame, and parallel pins extending from said bars, with a space between their outer ends for supporting 15 the boots or shoes between them, substantially as described.

2. A rack for holding boots and shoes, consisting of an open frame-work made up of a suitable base and end sections, horizontal supporting-bars pivoted in the end sections, and parallel pins supported at one end from said bars for holding the boots and shoes, substantially as described.

3. A rack for holding boots and shoes, consisting of an open frame-work made up of a suitable base and end supports, a series of horizontal supporting-bars, and pins extending from said bars in pairs, with a space between the pins of each pair for receiving the upper 30 of the shoe, each shoe being held separately, substantially as described.

4. In combination with a suitable frame-work, horizontal pivoted bars, pins extending from said bars to support each boot and shoe, 35 and a bar, N, connecting the rear ends of the pins of each series together, and a vertically-movable connecting-bar, S, for two or more of

the bars N of the same series, whereby the holding-racks formed by the pins e may be shifted to change their position from a horizontal to an inclined position, substantially as described.

5. In combination with a suitable frame-work, horizontal pivoted bars H, pins projecting therefrom for supporting the boots and 45 shoes, horizontal bars N for connecting the rear ends of said pins, whereby the pins of each series may be tilted on the pivot of the bar H, and a locking-plate for holding the racks in an inclined position, substantially as described. 50

6. In combination with a suitable frame-work, horizontal bars H, pins projecting therefrom for supporting the boots or shoes, horizontal bars N for connecting the rear ends of the pins of each series, a movable connecting-bar, S, for two or more of the bars N of each series, and a pivoted locking-plate, h, for holding the pins in an inclined position, substantially as described.

7. In combination with a suitable frame-work, horizontal bars H, pins projecting therefrom for supporting the shoes between them, horizontal bars N for connecting the rear ends of the pins, movable bars S, connecting the series of bars N, and the pivoted locking-plate 65 h, having a shoulder, n, and being under spring-tension, substantially as described.

Signed at Lynn, Massachusetts, in presence of two witnesses.

SAMUEL L. SAUNDERS.
